UNITED STATES PATENT OFFICE.

HARRY NEVILLE, OF NEW YORK, N. Y., ASSIGNOR TO NATHAN MANUFACTURING COMPANY, OF NEW YORK, N. Y., A CORPORATION OF NEW YORK.

VACUUM-PUMP.

1,101,143.

Specification of Letters Patent. Patented June 23, 1914.

Application filed February 25, 1914. Serial No. 820,913.

To all whom it may concern:

Be it known that I, HARRY NEVILLE, a citizen of the United States, residing at New York, in the county and State of New York, 5 have invented certain new and useful Improvements in Vacuum-Pumps, of which the following is a specification.

This invention relates to pumps adapted to exhaust air from receptacles and is particularly constructed for use in connection with the "safety apparatus for steam boilers" shown in Patent #1,015,703 issued to myself on January 23, 1912, and its exact construction and mode of operation is more 15 specifically set forth hereinafter.

To insure the proper working of the device shown in Patent #1,015,703, it is absolutely essential that air be exhausted from the mercury holding cup. Any air or gases 20 confined in the upper interior part of this cup expand to a greater degree than the mercury and push the operating piston in an upward direction sooner than intended and thereby operate the alarm prematurely.

25 To create a vacuum in the mercury cup in a simple and efficient manner is the purpose of my invention, the construction and application of which is explained by reference to the accompanying drawings in which:

30 Figure 1 shows a sectional view of the mercury holding cup of the safety apparatus with my pump mounted thereon, and Fig. 2 is a horizontal cross section of a part of the pump taken along the plane of line 2—2 35 in Fig. 1. Fig. 3 shows a sectional view of a modification of a part of the pump.

Like characters of reference refer to similar parts throughout the several views and the following specification:

40 1 is a mercury holding cup, mainly cylindrical in shape. Its upper portion is threaded internally at 2, to receive a cap 3, which is provided with a central bore 4. An annular flange 5 makes a tight joint between 45 cap 3 and mercury cup 1. The upper end of cap 3 is threaded externally and the upper end of bore 4 increased to a larger diameter as shown at 6. An operating piston 7 is adapted to be slidably mounted within bore 50 4 of cap 3.

All the parts so far specified are more fully described and their respective functions explained in detail in Patent #1,015,703 above referred to.

I shall now proceed with the description 55 of a preferred construction of my air exhausting pump. A socket 8 is threaded internally at its base at 9 to engage with the upper portion 6 of cap 3. Its exterior is preferably of polygonal cross section, as 60 shown in Fig. 2 to provide gripping surface for a wrench to facilitate screwing onto the mercury cup. An extension 10 of socket 8 is threaded externally to receive a packing nut 11, adapted to compress suitable packing material 12. A bore 13 extends longitudinally through socket 8, its diameter being somewhat larger than that of the operating piston 7 for reasons set forth herein- 65 after.

70 14 is an opening affording means of communication between bore 13 and a barrel 15 which is preferably screwed into socket 8 at 16, but may also be made part of and integral with socket 8.

75 17 is a plunger head which may be secured to an operating rod 18 by washers 19 and 20 and lock nut 21 or any other convenient means.

22 is a closure for barrel 15 provided with 80 an opening 23 larger in diameter than the plunger rod 18.

Fig. 3 shows a modified construction of socket 8 in which the externally threaded extension 10 has been omitted and the diameter of the bore 13 above the port 14 reduced as shown at 25, so as to frictionally engage the operating piston 7.

85 The operation of the device is as follows: The pump is screwed onto the mercury cup 90 1 as shown in Fig. 1. The piston 7 is inserted into bore 13 in approximately the position shown. The packing 12 is then tightened by means of nut 11 just enough to 95 allow the operating piston 7 to slide and at the same time resist the atmospheric pressure. Now the plunger 17 is pulled out. When same is out about half way the operating piston 7 is pushed down quickly into bore 4, at the same time the outward stroke 100 of the plunger 17 is being completed. It can readily be seen that the outward stroke of the plunger 17 will exhaust any air which is confined in the space 24 on top of the mercury in the cup 1 and any air in the 105 space between the outside diameter of piston 7 and the diameter of bore 13 in socket 8. The piston 7 being pushed down during the

2
period of exhausting the air will enter a vacuum in the mercury cup and being in frictional contact with cap 3 will effectually prevent any air from entering the mercury cup after the pump has been removed.

5 Various changes in the form, proportion and minor details of construction may be resorted to without departing from the principle or sacrificing any of the advantages of 10 the invention as defined in the appended claims.

What I claim as new is:

1. In combination with an expansive element container and an operating piston of 15 the character described, a socket adapted to be fastened onto said container, a bore through said socket, air excluding means on top of said bore and a port connecting said bore with means for exhausting air from 20 the upper interior portion of said container while inserting said operating piston into said container.

2. In combination with an expansive element container and an operating piston of 25 the character described, a socket adapted to be fastened onto said cup, a bore extending through said socket, air excluding means on top of said bore, a port connecting said bore with the barrel of a pump, adapted to exhaust air from the upper interior portion of 30 said container while inserting said operating piston into said container.

3. In a socket, a bore extending through same, air excluding means on top of said bore in combination with an operating piston of the character described, air exhausting means connected to said bore, and means for fastening said socket onto a receptacle.

4. In a socket member for a vacuum pump, 40 a bore extending through same, air excluding means on top of said bore in combination with an operating piston of the character described, a port connecting said bore

with the barrel of the pump and means for fastening said socket onto a receptacle.

5. In combination with a vacuum pump, 45 a socket adapted to be fastened onto a receptacle, a bore through said socket, suitable packing means on top of said bore, and a port connecting said bore with the pump.

6. In combination, a plunger, a pump barrel, a socket adapted to be fastened onto a receptacle, a bore extending through said socket, means for compressing packing on top of said bore, and a port connecting said 55 bore with the barrel of the pump.

7. In combination with a pump of the character described, a socket adapted on one end to be fastened to a receptacle, the other end of said socket threaded externally, packing means engaging said externally threaded end of said socket, a bore connecting said two ends of said socket, and a port connecting said bore with the pump.

8. In combination with a pump of the character described, a socket adapted on one end to be fastened to a receptacle, a bore extending through said socket, a port connecting said bore to the pump, said bore having a reduced cylindrical portion above said 70 port.

9. A vacuum pump comprising a plunger, a plunger rod, a pump barrel, a socket, a bore extending through said socket, means for compressing packing on top of said bore, means for fastening said socket to a receptacle at the bottom of said bore, and a port connecting said bore to said pump barrel.

75 In testimony whereof I have hereunto set my hand in presence of two subscribing witnesses.

HARRY NEVILLE.
